NOVELTY AND AMUSEMENT BRUSH MEMBER
Carl Ayala, Chicago, Ill., assignor to H. Fishlove & Co.,
Chicago, Ill., a corporation of Illinois
Filed Oct. 23, 1964, Ser. No. 405,956
6 Claims. (Cl. 272—8)

One of the objects of this invention is to provide a novelty and amusement device which gives to the observer the impression that a surface is being defaced by a strip or dab of paint, when in fact as the paint-brush is moved over the surface, ostensibly in the act of defacing the surface, a strip of material simulating a paint is applied to the surface, which strip is subsequently removed without any defacement to the surface to which it is applied.

Another object of this invention is to provide a novelty and amusement device which tends to give the realistic impression that a dab or strip of paint has been applied to a surface and the surface defaced. Obviously, if someone took a paint-brush and moved it across a wall surface or a painting or an important document or the like, and upon removing the brush it appeared that the surface had been defaced by what appeared to be a strip or dab of paint, the observer would be astonished, shocked and surprised. When the observer would subsequently realize what had really transpired he would be amused.

Another object of this invention is to provide a very simple and inexpensive novelty and amusement device of the foregoing character.

Other objects will become apparent as this description progresses.

In the drawings:

FIG. 1 is a perspective view of the device forming this invention.

FIG. 2 is a view showing the manner of using this device.

FIG. 3 is an end elevational view taken on lines 3—3 of FIG. 1.

FIGS. 4 and 5 are end elevational views of the progressive steps in using this device.

FIG. 6 is a view of the pressure sensitive strip before it is removed for use with the brush, and

FIG. 7 is a view of a modification.

Referring to the embodiment shown in FIGS. 1 to 7 inclusive, the numeral 10 designates what would appear to be a normal and conventional paintbrush having a conventional type of handle 12, conventional bristles 14, and a conventional band or sleeve-like member 16, formed of metal or the like, which surrounds the upper portion of the bristles and the lower portion of the handle. The brush of this invention is intended to be as close in appearance and general construction to a conventional paintbrush to carry out the purpose and effect of the present invention.

On one of the sides of the brush there is provided a clip or holder, generally designated by the numeral 18, which may be in any form so that it provides a slight gripping surface for the strip of material to be held therein. As shown in FIG. 1, the holder 18 may be struck from the band or sleeve 16 to form an offset strip 20, offset from the plane of the side of the band 16, thereby forming top and bottom slots 22 for receiving and removably holding the adhesive strip, generally designated at 24.

The strip of material 24 has a pressure sensitive adhesive coated surface 26 on one side, with the opposite side 28 uncoated and non-adhesive. The uncoated and non-adhesive side 28 can be colored with any suitable color. The strip 24 when applied to a surface or object, as will be explained, is intended to give the visual impression that it is a coating or dab of paint. The side

2

and end border edges 30 of the strip are of irregular shape to further aid in carrying out this impression, as can best be seen in FIG. 2.

The strip of material 24 is positioned against the side 5 of the brush having the strip holder or clip 18, with the non-adhesive side 28 facing inwardly towards the side of the brush and with the adhesive side 26 facing outwardly. The strip is slid into and through the slots 22 and is grippingly held in place by the strip holder 18, as shown in FIG. 1. The strip 24 is of a dimension less than the side of the brush and is hidden from view when looking at the brush from the opposite side.

In the application or performance of this invention, the brush is held in the hand by the handle so that the strip 24 is hidden from view. That is, the brush is held so that the strip 24 faces the person holding the brush and away from the view of the observer. The person applies it against a surface, moving it over the surface in much the same manner as one would do when painting. As the brush is moved over the surface of the wall or painting or other object, as indicated by the numeral 32, the operator presses down on the brush so that the adhesive coated surface 26 of the strip 24 will engage the surface 32 to which it is applied, and as the operator moves the brush across the surface in a conventional painting manner, the adhesive surface 26 sticks to the surface 32 and remains on the surface 32, becoming detached from the strip holder 18 which holds it under slight pressure. The strip 24 is thus adhesively secured to the surface 32 and lies perfectly flat against the surface 32. Thus, to the observer viewing the surface 32 after the brush has been moved across, the impression is conveyed that a strip or dab of paint has been applied to the surface and defaced it. This gives a startling impression.

If a paintbrush with black bristles is to be used then the face 28 of the strip which will be exposed after the brush is moved across the surface should likewise be black. The exposed color of the face 28 of the strip should correspond to the color of the bristles to simulate the effect that the bristles containing paint have been moved across the surface. After the amusement novelty device has served its purpose, the strip 24 may be removed from the applied surface 32 and repeatedly used for other observers.

To protect the pressure sensitive adhesive coated strips 24 until just prior to use, each strip 24 is preferably secured to an individual backing sheet 34, as shown in FIG. 6, from which it may be removed. Several of such strips and sheets are supplied with each brush.

FIG. 7 shows a modified manner of holding the strip 24 on the brush. In this modification, the band or sleeve 16 is stamped or struck-out to form a tongue or clip 36 which serves to grippingly hold the strip 24 in the manner previously described. Various other means may be provided for detachably holding the strip 24 against the side of the brush.

It will be understood that various changes and modifications may be made from the foregoing without departing from the spirit and scope of the appended claims.

What is claimed is:

1. A novelty and amusement device comprising, a brush member, securing means on one side of said brush member, a strip releasably held by said securing means against said side of the brush with the strip hidden from the view of an observer, adherent means on the side of said strip spaced from said brush, said strip adapted to be applied and adhered to a surface by moving said brush across said surface, said strip when applied to said surface giving the impression that the surface has been defaced by a paint.

2. A structure defined in claim 1 in which said adherent means is adhesive.

3. A structure defined in claim 1 in which the strip surface facing said side of said brush is colored with a color corresponding to that of the brush bristles.

4. A structure defined in claim 1 in which the securing means is a clip.

5. A structure defined in claim 1 in which the securing means has a slot to permit insertion of the strip.

6. A structure defined in claim 1 in which said adherent means is a pressure sensitive adhesive coated surface.
